UNITED STATES PATENT OFFICE

2,121,383

COSMETIC CONTAINER

Benjamin F. Conner, West Hartford, Conn., assignor to Colt's Patent Fire Arms Manufacturing Co., Hartford, Conn., a corporation of Connecticut

Application February 11, 1937, Serial No. 125,309

8 Claims.

(CL 215—1)

This invention relates primarily to cosmetic containers of the type disclosed in my patent for Jars, No. 2,076,549, dated April 13, 1937, which containers are primarily intended for containing cosmetic preparations which may be powders, or salves, cold creams and other preparations of a paste-like consistency. A container of this type consists of at least two separate members, each of which may be molded from a material of the 5 synthetic resin class. The inner member is formed for engagement with a closure cap and is adapted for containing the cream or other cosmetic preparation; and the base or outer structure serves to support the inner or containing member and to provide at least a part of the desired exterior contour or design.

The principal object of the present invention is to provide a container of the general class referred to but having two or more containing 20 members arranged at approximately the same level and all connected with a common base or outer structure. The base or outer structure preferably comprises two separate members, that is a bottom or base member, and an enclosing member having a top wall with openings therein for receiving the containing members.

A further and more specific object of the invention is to provide a container of the class defined 30 having containing members of different sizes or depths, but arranged with their tops at approximately the same level.

In the accompanying drawings I have shown several embodiments of the invention, but it will be understood that the drawings are intended for 35 illustrative purposes only and are not to be construed as defining or limiting the scope of the invention, the claims forming a part of this specification being relied upon for that purpose.

Of the drawings:

Fig. 1 is a plan view of a container embodying the invention, one of the containing members being omitted.

Fig. 2 is a side view of the container as shown in Fig. 1 with certain portions shown in vertical longitudinal section.

Fig. 3 is a view showing the several parts of the container separated from each other.

Fig. 4 is a bottom view of one of the containing members.

Fig. 5 is a side view showing an alternative container embodying the invention, portions of the base member and of the enclosing member being shown in vertical longitudinal section.

Fig. 6 is a fragmentary view similar to the right

hand portion of Fig. 5 but showing another alternative embodiment of the invention.

Figs. 7 and 8 are bottom and top views respectively of the adapter shown in Fig. 6.

Fig. 9 is a plan view of another alternative 5 container embodying the invention.

Fig. 10 is a side view of the container shown in Fig. 9, portions of the enclosing member and of one of the closure caps being shown in vertical longitudinal section.

In the drawings, particularly in Figs. 1 to 4, I have shown a container having a plurality of containing members 1, 1 arranged at the same level. Three such members are shown, but I do not limit myself as to the number. The members 15 1, 1 are shown as being of the same size but as to this there may be variation.

Each containing member 1 is preferably of such shape that its interior diameter at the top is at least as large as the interior diameter below the 20 top. The bottom wall of the containing member is indicated at 2, and the said member is threaded adjacent its upper periphery as indicated at 3, being thus adapted for engagement with a 25 threaded closure 4 of the cap type.

A common bottom or base member 5 is provided for all of the containing members, the said base member being beneath all of them. Means are provided for readily connecting the several containing members with the base member to 30 prevent relative rotation and to resist separation. The means which is shown and which is now preferred is disclosed and specifically claimed in my patent for Jars, No. 2,077,215, dated April 13, 1937, but it will be understood that I do not 35 herein narrowly limit myself as to the details of the connecting means.

Projecting downward from the bottom wall 2 of each containing member 1 are four relatively small plugs 6, 6 which are located at uniform 40 distances from the axis of the member and which are preferably spaced apart uniformly or substantially so. Formed on the base member 5 are groups of sockets for receiving the plugs on the respective containing members. In each group 45 there are four sockets 7, 7 of such size and so positioned as to be adapted to receive the corresponding plugs 6, 6. On account of the substantially uniform spacing of the plugs and sockets it is possible for each containing member to be 50 assembled in four angularly different positions. While the plugs and sockets are substantially uniformly spaced from each other as already stated, they may vary slightly from such uniformity in order to provide increased friction of 55

engagement, as explained in detail in my last aforesaid patent.

Preferably the several plugs 6, 6 have their main body portions smaller than the sockets and are provided with a plurality of narrow vertical fins 8, 8 which project radially outward from the body of the plug. These fins provide narrow bearing surfaces for engagement with the walls of the sockets, and they tend to cut into the socket walls to provide a firmer engagement.

Preferably there is associated with the containing members 1, 1 and with the base member 5 a structurally separate enclosing member, the container being in this respect similar to that disclosed and claimed in my co-pending application for Jars, Serial No. 125,308 filed February 11, 1937. As shown there is an enclosing member 9 which rests upon the base member and which preferably conforms in general shape to the shape chosen for the base member. It has vertical or substantially vertical side walls 10 extending entirely around and enclosing the containing members, and it has a top wall 11 with openings 12 therein for receiving the said containing members.

Each containing member 1 preferably has formed integrally therewith an annular flange 13 with a downward opening rabbet 14 therein. The top wall 11 of the enclosing member 9 is so related to the flanges 13 on the container that the lower rabbeted portions of the flanges enter the said openings 12, the upper portions of the flanges overlying and engaging the said top wall. The enclosing member is thus held in place by engagement with the bottoms of the flanges on the containing members and with the top of the base member. It will be understood that the several members constituting the container are held in their assembled relationship by reason of the described engagement between the plugs 6, 6 and the sockets 7, 7. The enclosing member 9 is normally held between the base member and the containing members, but it is structurally separate from the said base and containing members and it is preferably without direct positive connection with either the base or the containing member.

The construction shown in Fig. 5 is similar to that shown in Figs. 1 to 4, the difference being that the containing members have different depths. As shown there are two containing members 1, 1 similar to those already described and a third containing member 1^a which differs from the members 1, 1 in that it has less depth. The base 5^a has a portion thereof elevated at 15 so that the sockets 7^a, 7^a of one group are at a higher level than those of the other groups so as to engage the plugs 6^a, 6^a on the containing member 1^a.

The construction shown in Figs. 6 to 8 is similar to that shown in Fig. 5 with the exception that there is provided a base 5 which may be exactly the same as that shown in Figs. 1 to 3. In order to connect the containing member 1^a with the base 5 there is provided an adapter disc 16 having on its top face sockets 17, 17 similar to the sockets 7, 7 and adapted to receive the plugs 6^a, 6^a on the containing member 1^a. On the bottom of the disc 16 are plugs 18, 18 adapted to enter the sockets 7, 7 on the base 5.

Figs. 9 and 10 show a container which is similar to that shown in Figs. 1 to 4 but which differs in that the central containing member 1^b is smaller in diameter and of less depth than the containing members 1, 1. Except for size the con-

taining member 1^b is similar to the containing members 1, 1, being provided with downward projecting plugs 6^b, 6^b and with a rabbeted annular flange 13^b. The containing member 1^b is threaded to engage a closure 4^b. The containing member 1^b instead of engaging the base 5, either directly or through an adapter, is supported entirely on the enclosing member 9^b which is specially formed to receive it. As shown, the enclosing member 9^b has a depression 19 in the top wall 10 11^b thereof. The bottom wall of the depression 19 is provided with holes adapted to receive and fit the plugs 6^b, 6^b and to thus hold the containing member 1^b in its normal position as shown in Fig. 10.

It will be apparent that a container embodying the invention is adapted to conveniently hold a plurality of cosmetic preparations which may be either powders or creams. The construction is such that various attractive and ornamental designs may be used, such designs involving not only ornamental shapes but various color combinations.

The container may be marketed without contents, and may be filled by the user with such cosmetic preparations as may be desired; or it may be sold with various combinations of cosmetic preparations contained therein. If sold with cosmetic preparations therein the manufacturer may find it advantageous to provide refill units each consisting of a containing member and closure with suitable contents. These refill units may be substituted by the user in the original container, thus making it unnecessary for the user to purchase an entire new container after the original contents have been used.

What I claim is:

1. The combination in a cosmetic container, of a plurality of thin-walled cup-shaped molded containing members positioned at approximately 40 the same level and each having its interior diameter at the top at least as large as is the interior diameter below the top, each of the said members being externally threaded adjacent its upper periphery for engagement with a closure of the 45 cap type, a common molded base member beneath all of the said containing members, retaining means formed integrally with the bottoms of the said containing members and connected with the said base member to hold the said members 50 against relative lateral movement and to resist relative upward movement of the containing members, and a common enclosing member structurally separate from the base member and from the containing members and surrounding all of 55 the latter, the said enclosing member having a top wall with openings therein for receiving the containing members.

2. The combination in a cosmetic container, of a plurality of thin-walled cup-shaped molded 60 containing members positioned at approximately the same level and each having its interior diameter at the top at least as large as is the interior diameter below the top, each of the said members being externally threaded adjacent its upper 65 periphery for engagement with a closure of the cap type and each of them having an outward projecting annular flange located immediately below the thread, a common molded base member beneath all of the said containing members and 70 extending radially in all directions at least as far as do the said flanges on the containing members, retaining means formed integrally with the bottoms of the said containing members and connected with the said base member to hold all 75

of the said members against relative lateral movement and to resist relative upward movement of the containing members, and a common enclosing member structurally separate from the base member and from the containing members and surrounding all of the latter, the said enclosing member having a top wall with openings therein for receiving the containing members and the said enclosing member being held in place by engagement with the top of the base member and with the bottoms of the flanges on the containing members.

3. The combination in a cosmetic container, of a plurality of thin-walled cup-shaped molded containing members positioned at approximately the same level and each having its interior diameter at the top at least as large as is the interior diameter below the top, each of the said members being externally threaded adjacent its upper periphery for engagement with a closure of the cap type and each of them having an outward projecting annular flange located immediately below the thread and also having downward extending vertical portions adjacent the bottom, a common molded base member beneath all of the said containing members and extending radially in all directions at least as far as do the said flanges on the containing members, the said base member having a plurality of means formed integrally therewith for engaging the said downward extending vertical portions on the respective containing members to hold all the said members against relative lateral movement and to resist relative upward movement of the containing members, and a common enclosing member structurally separate from the base member and from the containing members and surrounding all of the latter, the said enclosing member having a top wall with openings therein for receiving the containing members and the said enclosing member being held in place by engagement with the top of the base member and with the bottoms of the flanges on the containing members.

4. The combination in a cosmetic container, of a plurality of thin-walled cup-shaped molded containing members having different depths and positioned with their tops at approximately the same level and each having its interior diameter at the top at least as large as is the interior diameter below the top, each of the said members being externally threaded adjacent its upper periphery for engagement with a closure of the cap type and each of them having an outward projecting annular flange located immediately below the thread and also having retaining means formed integrally therewith near the bottom, a common molded base member beneath all of the said containing members and extending radially in all directions at least as far as do the said flanges on the containing members, a plurality of means at different levels on the base member for engaging the said retaining means on the respective containing members of different depths to hold all of the said members against relative lateral movement and to resist relative upward movement of the containing members, and a common enclosing member structurally separate from the base member and from the containing members and surrounding all of the latter, the said enclosing member having a top wall with openings therein for receiving the containing members and the said enclosing member being held in place by engagement with the top of the base member and with the bottoms of the flanges on the containing members.

5. The combination in a cosmetic container, of a plurality of thin-walled cup-shaped molded containing members having different depths and positioned with their tops at approximately the same level and each having its interior diameter at the top at least as large as is the interior diameter below the top, each of the said members being externally threaded adjacent its upper periphery for engagement with a closure of the cap type and each of them having an outward projecting annular flange located immediately below the thread and also having retaining means formed integrally therewith near the bottom, a common molded base member beneath all of the said containing members and extending radially in all directions at least as far as do the said flanges on the containing members, the said base member having a plurality of means formed integrally therewith at different levels for engaging the said retaining means on the respective containing members of different depths, and a common enclosing member structurally separate from the base member and from the containing members and surrounding all of the latter, the said enclosing member having a top wall with openings therein for receiving the containing members and the said enclosing member being held in place by engagement with the top of the base member and with the bottoms of the flanges on the containing members.

6. The combination in a cosmetic container, of a plurality of thin-walled cup-shaped molded containing members having different depths and positioned with their tops at approximately the same level and each having its interior diameter at the top at least as large as is the interior diameter below the top, each of the said members being externally threaded adjacent its upper periphery for engagement with a closure of the cap type and each of them having an outward projecting annular flange located immediately below the thread and also having retaining means formed integrally therewith near the bottom, a common molded base member beneath all of the said containing members and extending radially in all directions at least as far as do the said flanges on the containing members, the said base member having a plurality of means formed integrally therewith at the same level and each adapted for engaging the retaining means of a relatively deep containing member, at least one adapter interposed between one of the last said means on the base and the retaining means of a containing member of less depth, and a common enclosing member structurally separate from the base member and from the containing members and surrounding all of the latter, the said enclosing member having a top wall with openings therein for receiving the containing members and the said enclosing member being held in place by engagement with the top of the base member and with the bottoms of the flanges on the containing members.

7. The combination in a cosmetic container, of a plurality of thin-walled cup-shaped molded containing members positioned at approximately the same level and each having its interior diameter at the top at least as large as is the interior diameter below the top, each of the said members being externally threaded adjacent its upper periphery for engagement with a closure of the cap type and each of them having an outward projecting annular flange located immediately below the thread, a common molded base member beneath all of the said containing members and

- extending radially in all directions at least as far as do the said flanges on the containing members, retaining means formed integrally with the bottoms of the said containing members and connected with the said base member to hold all of the said members against relative lateral movement and to resist relative upward movement of the containing members, and a common enclosing member structurally separate from the base member and from the containing members and surrounding all of the latter, the said enclosing member having a top wall with openings therein for receiving the containing members and the said enclosing member being held in place by engagement with the top of the base member and with the bottoms of the flanges on the containing members, and a containing compartment additional to the said containing members and carried by the top wall of the enclosing member.
8. The combination in a cosmetic container, of a plurality of thin-walled cup-shaped molded containing members positioned at approximately the same level and each having its interior diameter at the top at least as large as is the interior diameter below the top, each of the said members being externally threaded adjacent its upper per-

iphery for engagement with a closure of the cap type and each of them having an outward projecting annular flange located immediately below the thread, a common molded base member beneath all of the said containing members and extending radially in all directions at least as far as do the said flanges on the containing members, retaining means formed integrally with the bottoms of the said containing members and connected with the said base member to hold all of the said members against relative lateral movement and to resist relative upward movement of the containing members, and a common enclosing member structurally separate from the base member and from the containing members and surrounding all of the latter, the said enclosing member having a top wall with openings therein for receiving the containing members and the said enclosing member being held in place by engagement with the top of the base member and with the bottoms of the flanges on the containing members, and an additional containing member structurally separate from the enclosing member and supported entirely upon the top wall thereof.

BENJAMIN F. CONNER.
